Fisher Towle Clapp & Sons Atlys:

UNITED STATES PATENT OFFICE.

CHARLES A. STUART, OF KENOSHA, WISCONSIN, ASSIGNOR TO SIMMONS COMPANY, OF KENOSHA, WISCONSIN, A CORPORATION OF DELAWARE.

DESIGN FOR A BEDSTEAD END.

56,635.

Specification for Design.

Patented Nov. 16, 1920.

Application filed March 8, 1920. Serial No. 364,298. Term of patent 14 years.

To all whom it may concern:

Be it known that I, CHARLES A. STUART, a citizen of the United States, residing at Kenosha, in the county of Kenosha and State of Wisconsin, have invented a new, original, and ornamental Design for a Bedstead End, of which the following is a specification, reference being had to the accompanying drawing, forming part thereof.

The figure is a perspective view of the foot end of a bedstead embodying my new design.

An important characteristic of my design is the central panel containing a skeleton frame work intermediate a pair of spaced, vertically-disposed filler bars or tubes, which extend from the horizontal upper and lower frame members.

Other important features of my design are the pairs of closely adjacent vertical fillers which are located in the otherwise open

space between the center panel and the corner posts.

Another important feature of my new design is the shape of the frame work composing the skeleton central panel, this comprising in the present instance an elongated oval extending from the top to the bottom rail and between the vertical filler tubes which border the central panel, said main oval being combined with a pair of curved members vertically tangent to each other at the center of the panel, a rosette or medallion being located at the center of the panel.

My design is of especial value where the frame members of the bedstead end frame are constructed of metallic tubing.

I claim:

The ornamental design for a bedstead end, substantially as shown and described.

CHARLES A. STUART.
